SINGLE-BOOM DERRICKS

Thomas R. Hall, Portland, Oreg., assignor to McCabe-Powers Body Company, Berkeley, Calif., a corporation of California

Filed Apr. 7, 1960, Ser. No. 20,769

9 Claims. (Cl. 212—35)

This invention relates in general to certain new and useful improvements in single-boom derricks and, more particularly, to single-boom derricks for use on vehicles and similar mobile platforms.

It is the primary object of the present invention to provide a single-boom derrick adapted for use on a vehicle and similar mobile platforms and capable of being swung into any selected position from a forward or so-called "transport" position to a downwardly inclined rearward position with respect to the vehicle.

It is another object of the present invention to provide a single-boom derrick of the type stated wherein the boom may, at any of its extended or elevated positions, be swung through a substantial arc with respect to the vehicle.

It is also an object of the present invention to provide a single boom derrick of the type stated wherein the boom can be simultaneously moved in both the vertical and horizontal directions.

It is a further object of the present invention to provide a hydraulically operated swingable boom for use on a vehicle or the like which may be easily and conveniently moved to a plurality of positions while in use.

With the above and other objects in view, my invention resides in the novel features of form, construction, arrangement, and combination of parts presently described and pointed out in the claims.

In the accompanying drawings—

FIG. 1 is a fragmentary side elevational view of a truck employing a horizontally and vertically swingable boom constructed in accordance with and embodying the present invention;

FIG. 2 is a fragmentary perspective view showing the pivoting and actuating structure forming a part of the present invention;

FIG. 3 is a fragmentary sectional view taken along line 3—3 of FIG. 2;

FIG. 4 is a fragmentary perspective view of the means for pivotally connecting the driving cylinder to the body of the truck;

FIG. 5 is a fragmentary sectional view taken along line 5—5 of FIG. 2;

FIG. 6 is a fragmentary sectional view taken along line 6—6 of FIG. 5;

FIG. 7 is a fragmentary sectional view taken along line 7—7 of FIG. 6;

FIG. 8 is a fragmentary sectional view taken along line 8—8 of FIG. 2;

FIGS. 9 and 10 are fragmentary sectional views taken along lines 9—9 and 10—10, respectively, of FIG. 1;

FIG. 11 is a fragmentary sectional view taken along line 11—11 of FIG. 6; and

FIGS. 12, 13, and 14, are fragmentary sectional views taken along lines 12—12, 13—13, and 14—14, respectively, of FIG. 1.

Referring now in more detail and by reference characters to the drawings, which illustrate a practical embodiment of the present invention, A designates a vehicle including a chassis 1 and body 2 having rear vertical walls 3 and horizontal top-walls 4. The particular vehicle A, being a so-called "utility work body," contains a plurality of door-closed tool compartments 5, 6, 7, 8, which are conventional and are not a part of the present invention. The chassis 1 extends rearwardly beneath the walls 3 and

2

is provided with depending pivot-brackets 9 swingably supporting jacks 10 having cylinders 11 and piston rods 12, which are, in turn, provided with ground-engaging foot plates 13.

5 Welded or otherwise securely mounted on one of the top-walls 4 is an elongated anchor channel 14 provided centrally with a bracket 15 having a pair of aligned apertures 16, 17. A sleeve 18 is rigidly secured to the bracket 15 in alignment with the aperture 17 for purposes presently more fully appearing. Rigidly attached to the anchor channel 14 in substantial alignment with the bracket 15 and extending upwardly therefrom is a retention clip 19 bent laterally inwardly at its upper end in the provision of a guide ear 20. The clip 19 is strengthened by a gusset plate 21 which extends transversely between the lower portion of the clip 19 and the forward face of the bracket 15. The gusset plate 21 integrally includes a triangular camming-ear 22 which projects above the bracket 15 and is laterally spaced from the ear 20 of the clip 19, as best seen in FIG. 3 and for purposes presently more fully appearing.

Welded to the rearwardly presented end of the walls 3, which are directly adjacent to the anchor channel 14 and also extending vertically above the chassis 1, is an elongated U-shaped upright 23 which includes a bight 24 and a pair of spaced parallel flanges 25, 26, which are, in turn, provided intermediate their upper margins 29, 30, and their lower margins 27, 28, with aligned elongated notches 31, 32. Welded to the flanges 25, 26, of the upright 23 30 and flush along its upper face with the upper margins 29, 30, is a vertical bearing sleeve 33, which projects rearwardly beyond the rear vertical margins of the flanges 25, 26. In like manner, a lower bearing sleeve 34 is welded to the flanges 25, 26, in downwardly spaced relationship from, and in axial alignment with, the sleeve 33. A flat ring-like thrust plate 35 is welded to the upper margin of the sleeve 33 and also to the upper margins 29, 30, of the flanges 25, 26, the aperture 36 of the plate 35 being of the same diametral size as the inner diametral size of the sleeves 33, 34, and being in alignment therewith. As will be seen by reference to FIG. 2, the sleeves 33, 34, are located respectively above and below the notches 31, 32, so as to provide clearance forwardly of the centerline of the sleeves 33, 34.

45 The flange 25 is provided with an additional rectangular notch 36 which is spaced below the lower sleeve 34 and to which is welded a rectangular spanning plate 37, the spanning plate 37 extending between the flanges 25, 26, in parallel relationship to the bight 24 and being welded along opposite margins to the flange 26, and to the inner margin 38 of the notch 36. Welded to and extending rearwardly from the spanning plate 37 is a U-shaped cover 39 which extends inwardly toward the longitudinal axis of the vehicle A past the inner margin of the flange 25 and which is provided with a flat bight portion 40 which is parallel to the spanning plate 37. The spanning plate 37 and the bight 40 are provided with a pair of aligned apertures 41, 42, the aperture 42 on the bight 40 being partially surrounded by a pair of parallel rearwardly extending ears 43, 44, one of each of said ears being placed on opposite sides of the aperture 42 and each respectively being provided with an aligned aperture 45, 46, the apertures 45, 46, being sized for insertion of a conventional cotter pin 47. A conventional pulley-wheel 48 is inserted between the spanning plate 37 and the bight 40 of the cover 39 and is rotatably held therebetween by a bearing 49 which is mounted on a pin 50, the pin 50 being also inserted through the apertures 41, 42, and having a diametral bore 51 which is aligned with the apertures 45, 46, when the pin 50 is in operative position so as to receive the cotter pin 47. It should be noted that the

pulley-wheel 48 is substantially tangent to the vertical centerline of the bearing sleeves 33, 34.

Rotatably mounted in the sleeves 33, 34, is a vertical tubular post or shaft 52 provided at its upper end with a horizontal cap-plate 53 having a downwardly presented flat face 54 which bears against the upper surface of the thrust plate 35. Welded on the outer periphery of the shaft 52 and extending radially outwardly therefrom in spaced parallel relationship are a pair of aligned ears 55, 56, respectively, provided with aligned apertures 57, 58, the centerline of which is perpendicular to, and in rearwardly spaced relationship from, the centerline of the shaft 52. The ears 55, 56, are located on the cylindrical shaft 53 in such position that as the rotating column 52 rotates within the sleeves 33, 34, the ears 55, 56, enter the notches 31, 32, in the flanges 25, 26, thereby providing sufficient clearance to permit at least 180° of rotation for the shaft 52. The cap-plate 53 is annular and includes a laterally extending horizontal arm 59 provided at its outer end with a bore 60. Welded to and extending upwardly from the cap-plate 53 are spaced parallel inclined ears 61, 62, the ear 62 and the arm 59 being mutually reinforced by a gusset plate 63, which extends vertically therebetween. It should be noted that the anchor channel 14 is attached to the upright 23 in such manner that in the area of attachment no portion of the anchor channel 14 extends above the upper margins 29, 30, of the upright 23, whereby to provide rotational freedom for the rotating shaft 52.

Preferably, though not necessarily, the under face 54 of the cap-plate 53 is lined with a split thrust washer 64 held in place by drive pins 65, whereby to reduce the friction between the cap-plate 53 and the thrust plate 35. The shaft 52 extends slightly below the sleeve 34, and is provided on such downwardly extended end with a removable retainer plate 66 which is annularly larger than the shaft 52 and, therefore, prevents the shaft 52 from sliding upwardly out of journaled engagement within the sleeves 33, 34.

Rockably secured to the radially extending arm 59 of the shaft 52 by means of a pin 67 mounted in the bore 60 is a double acting hydraulic cylinder or so-called hydraulic ram 68 having a piston rod 69 slidably movable therein and being adapted, upon appropriate application of hydraulic fluid, to move in either direction within the cylinder 68. The hydraulic cylinder 68 is conventional and it is, therefore, sufficient for present purposes to state merely the function of the hydraulic cylinder and the fact that it is provided with conventional valve and conduit means for connecting the chamber within the cylinder on either side of the piston to a source of hydraulic fluid under pressure. The piston rod 69 extends outwardly from the cylinder 68 and is provided on its outer end with a collar 70 having a transverse bore 71 for receiving a pin 71' by which it is operatively secured in the bracket 15, the pin 71' being disposed at its upper and lower ends in the apertures 16, 17. It should be noted that the hydraulic cylinder 68 is placed on top of the arm 59, so that, as the piston rod 69 is extended and retracted within the hydraulic cylinder 68, the shaft 52 will rotate about its vertical axis or centerline.

Disposed between the inclined ears 61, 62, of the shaft 52, and swingably supported therefrom, is a derrick leg 72 having a main body 73 preferably comprising a pair of spaced lateral flanges 74, 75, integrally connected by a bight 76 and a spaced parallel transverse web 77 in the formation of a tubular channel 78 of internal square cross-section. As will be seen by reference to FIG. 2, the flanges 74, 75, extend outwardly beyond the web 77 and are provided, approximately midway between the ends of the leg 72, with aligned apertures 79, 79'. At the lower end 80 of the derrick leg 72, the flanges 74, 75, are provided with a second set of aligned apertures 81, 82, for receiving a pin 83, by which the derrick leg 72 is pivotally connected between the ears 61, 62. Con-

ventional washers 84, 85, are interposed between the ears 61, 62, and the flanges 74, 75, of the derrick leg 72, and a pulley-wheel 86 and a tubular bearing sleeve 87 are operatively mounted on the pin 83 between the flanges 74, 75, and held in spaced relationship therefrom by conventional spacers 88, 89. It should be noted that the pulley-wheel 86 is substantially tangent to the vertical centerline of the bearing sleeves 33, 34, and shaft 52. It should be noted that the bight 76 and web 77 are each provided with centrally located notches 90, 91, whereby to provide free rotation of the pulley-wheel 86.

Disposed within the tubular channel 78 is a second double-acting hydraulic motor or so-called hydraulic ram 92 secured at its inner end to the derrick leg 72 by a transverse pin 93 extending through apertures 94, 95, in the flanges 74, 75. The hydraulic motor 92 includes a conventional cylinder 96 which projects beyond the derrick leg 72 and is provided with a conventional piston rod 97, which is, in turn, provided at its outer end with a fitting 98 having an axially projecting ear 99 with a transverse bore 100 therein for receiving a pintle 101 by which the piston rod 97 is operatively connected to an elongated boom 102.

The boom 102 extends upwardly and downwardly from the pintle 101 and is pivotally connected at its lower end to the upper end of a link 103 which is in turn, pivotally mounted at its lower end upon a horizontal pintle 104 operatively mounted in the ears 55, 56. Adjacent its upper end, the link 103 is provided with upwardly projecting ears 105, 106, for accommodating a horizontal pintle 107, which is pivotally engaged in the lower end of a cross-link 108, the latter being also pivotally connected at its upper end upon a pintle 109 mounted in the apertures 79, 79', of the flanges 74, 75.

At its upper end, the boom 102 is conventionally provided with a sheave block 110 consisting of spaced parallel plates 111, 112, which support a pintle 113 and pulley-wheel 114 around which a winch cable 115 is trained.

In use, the parts are operatively connected as described and the boom assembly is transported on top of the vehicle A in the retracted position wherein the boom 102 and derrick leg 72, with the piston rod 97 fully retracted, are located in forwardly extended substantially horizontal position over the body 2. In this position, the derrick leg 72 will be held by the clip 19, which serves to prevent the boom assembly from inadvertently swinging to the side during transport. To extend the boom assembly and put it in the operative position, hydraulic fluid is applied to the cylinder 68, whereupon the derrick leg will pivot upwardly about the pin 83 and the boom 102 through the interconnecting links 103 and 108 will swing rearwardly and upwardly along an arcuate path. When the piston rod 97 is in the fully extended position, the boom 102 will extend rearwardly from the vehicle body 2 with the sheave block 110 near the ground, whereupon the cable 115 may be routed about the pulley-wheel 86 down through the tubular shaft 52 and around the pulley-wheel 48. One end of the cable 115 is conventionally attached to a load to be hoisted and the other end of the cable 115 is wound upon a conventional winch (not shown). After the boom 102 and derrick leg 72 have been elevated above the upper limits of the clip 19, the first hydraulic cylinder 68 may be operated by the application of hydraulic fluid to cause the shaft 52 to rotate about its vertical axis or centerline within the limits defined by the forwardmost margins of the notches 31, 32. It is to be noted that two hydraulic cylinders or motors 68, 92, are independent of each other and may be individually or conjointly operated.

To place the boom assembly in the transport position, it is merely necessary to bring the shaft 52 in proper position by operation of the hydraulic cylinder or motor 68, and the hydraulic motor 92 may be operated to cause the piston rod 97 to retract therein and thereby swing the boom 102 and the derrick leg 73 forward over the vehicle

A, until the derrick leg 73 rests on the gusset plate 21 between the clip 19 and the bracket 15, substantially as shown.

It should be understood that changes and modifications in the form, construction, arrangement, and combination of the several parts of the single-boom derricks may be made and substituted for those herein shown and described without departing from the nature and principle of my invention.

Having thus described my invention, what I claim and desire to secure by Letters Patent is:

1. A laterally and vertically swingable derrick comprising a base, a vertical post rotatably mounted on said base and adapted to rotate thereon about a substantially vertical axis, a laterally projecting substantially horizontal arm rigidly attached to the post, first hydraulic ram means pivotally mounted at one end on the base having rocking movement in a substantially horizontal direction and being operatively connected at its other end to the laterally projecting arm for rotating said post about said vertical axis, a derrick leg pivotally mounted on the top of said post for swinging movement up and down about a substantially horizontal axis located about the upper end of the post and in an arc across the top of the post from an inoperative position to an operative position, a boom, a second hydraulic ram means securely mounted in said derrick leg and having an extensible element adapted to extend outwardly from the swinging end of the derrick leg upon application of fluid pressure to the second hydraulic ram means, said extensible element being pivotally connected at its outer end to said boom for swinging movement about a substantially horizontal axis, first link means pivotally connected at its outer end to said boom and being connected at its inner end to said post in downwardly spaced vertical relation with respect to said derrick leg, second link means pivotally connected to the first link means and the derrick leg so that, as said extensible element is extended, said derrick leg will simultaneously swing up and down together with respect to said post.

2. A laterally swingable derrick for use with a truck having a rear platform provided with a compartment including a rear wall and a top wall, said derrick comprising a channel having a pair of spaced parallel walls and being rigidly secured to said rear wall, an anchor plate secured to said top wall and said channel, a pair of aligned sleeves rigidly secured in spaced vertical relation between the parallel walls of said channel, the upper sleeve being in flushwise alignment with the upper end of said channel, a cylindrical post having a flange on its upper end rotatably mounted in said aligned sleeves and having an arm extending radially outwardly therefrom, said post also being provided with a first pair of spaced parallel ears at its upper end and having a second pair of spaced parallel ears extending radially outwardly therefrom intermediate its ends between the sleeves, a derrick leg mounted on one end to said post between said first pair of ears for pivotal movement about a horizontal axis, a first hydraulic cylinder mounted in said derrick leg and having a movable piston rod extending outwardly therefrom, said first cylinder being adapted to cause said piston rod to extend and retract upon selected application of hydraulic power from an external source, said piston rod being extendable from the swinging end of the derrick leg, a first link pivotally mounted at one end to said second pair of ears, a boom pivotally connected at one end to the first link and also being connected to the piston rod at a point substantially near the other end of said boom, a second link pivotally connected at one end to the first link and also being pivotally connected to the derrick leg, whereby as the piston is extended from the first cylinder means, the first link pivots in the second pair of ears and the derrick leg pivots in the first pair of ears, and the boom is moved vertically, and a second cylinder also having an extensible piston rod and being connected at opposite

ends to said arm and said anchor plate for forced rotation of the post about a vertical axis in said sleeves.

3. The derrick of claim 2 wherein the end of the piston of the second cylinder is pivotally connected to the anchor plate and the opposing end of the cylinder is pivotally connected to the arm on said post.

4. The derrick of claim 2 wherein the axes on the first link about which the boom and the second pair of ears are pivoted are coplanar.

10 5. The derrick of claim 2 wherein the two axes on the first link about which said first link is respectively pivoted to the boom and the second pair of ears define a plane, and the axis of pivotal connection between the first link and second link is offset from said plane and parallel thereto.

15 6. The derrick of claim 2 wherein the end of the piston rod on the first cylinder and the axis about which the derrick leg pivots on the vertical post define a plane, and the axis about which the second link pivots with respect to said derrick leg is parallel to and offset from said plane.

20 7. The apparatus of claim 2 wherein a sheave block is operatively mounted on the end of the boom, a first pulley-wheel is operatively mounted between the first pair of spaced ears, a second pulley-wheel is operatively mounted on said channel beneath the first pulley-wheel, and a cable is trained over the sheave block and the first and second pulley-wheels and is operatively wound on a remote winch, said first and second pulley-wheels being so located 25 that the cable is routed coaxially with respect to the vertical axis of rotation for the derrick, whereby when a load is placed on the cable and the derrick is rotated horizontally, the cable remains substantially stationary and in operative connection with respect to the pulley-wheels.

30 8. A laterally and vertically swinging derrick for use with a vehicle or similar portable platform, said derrick comprising a post operatively mounted upon the vehicle for rotation about a substantially vertical axis, a laterally projecting substantially horizontal arm rigidly attached 35 to said post, a first hydraulic ram having one end pivotally mounted on the vehicle and having rocking movement in a substantially horizontal plane adjacent to the upper end of the post, the other end of said first hydraulic ram being pivotally attached directly to said laterally projecting arm for rotating said post about said vertical axis, a first derrick frame element operatively connected at one end to the upper end of the post so as to swing in an arc across the top of the post from transport position 40 to operative position, a second hydraulic ram operatively mounted on the first frame-element and having an extensible element adapted for movement lengthwise with respect to the first frame element, said extensible element having a pivot-forming member projecting outwardly from the first frame-element, a second derrick frame-element pivotally attached inwardly from its outer end to said pivot-forming member and being operatively connected at its inner end to the outer end of a rocking link which is pivotally connected at its other end to the post 45 in downwardly spaced relation to the first frame-element, and a transverse link pivotally connected at its opposite ends to the first frame-element and the rocking link respectively whereby to cause the two frame-elements and the rocking link to swing in unison.

50 9. A laterally and vertically swinging derrick for use with a vehicle or similar portable platform, said derrick comprising a post operatively mounted upon the vehicle for rotation about a substantially vertical axis, a laterally projecting substantially horizontal arm rigidly attached to said post, a first hydraulic ram pivotally mounted at one end on the vehicle and having rocking movement in a substantially horizontal plane adjacent to the upper end of the post, the other end of said first hydraulic ram being pivotally attached directly to said laterally projecting arm for rotating said post about said vertical axis, a first derrick leg pivotally mounted upon the upper end 55 70 75

of the post for vertically swinging movement about a horizontal axis from a transport position over the vehicle to an operative position outwardly in the clear beyond the vehicle, a second hydraulic ram operatively mounted on the first leg and having an extensible element adapted for movement lengthwise with respect to the first leg, said extensible element having a first pivot located outwardly from the first leg, a second derrick leg pivotally attached inwardly from its outer end to said first pivot, said first leg having a second pivot located intermediate the first pivot and said horizontal axis around which the first leg swings, said second pivot also being located substantially above a plane between the first pivot and said horizontal axis when the first leg is in transport position, said second leg when in transport position extending lengthwise along the first leg above the second pivot and projecting outwardly at its inner end beyond the post with respect to the first leg, the second leg being operatively connected at said inner end to the upper end of a rocking link which is pivotally connected at its other end to the post in down-

wardly spaced relation to the first leg, and a transverse link pivotally connected at its opposite ends to the second pivot and the rocking link respectively whereby to cause the two legs and the rocking link to swing in unison from transport position to operative position.
